UNITED STATES PATENT OFFICE.

CHARLES H. TOMPKINS, OF WASHINGTON, DISTRICT OF COLUMBIA.

CONCRETE-DISTRIBUTING SYSTEM.

Application filed July 29, 1925. Serial No. 46,852.

To all whom it may concern:

Be it known that I, CHARLES H. TOMPKINS, a citizen of the United States, residing at Washington, in the District of Columbia, have invented certain new and useful Improvements in Concrete-Distributing Systems, of which the following is a specification.

The present invention relates to apparatus for distributing concrete and to a system especially designed to take care of construction projects involving considerable magnitude and in which the materials must be conveyed to points of deposit remotely related to the mixing plant.

In the majority of systems in operation at the present time, the gravitation method of delivery is utilized and no great problem of engineering is encountered, so long as the range of distribution remains within the usual short radius distance of approximately 100 feet.

Under such conditions, it is customary to employ an elevator tower in which the mixed materials are hoisted and dumped into a chute line composed generally of a plurality of sections, certain of which are supported from the tower by a boom, while the remaining ones are sustained by poles set on the ground. As the distance increases beyond the range mentioned, it obviously is impracticable to use the boom system of support, because of the leverage and dangerous strains upon the tower, so that where the project extends to several hundred feet or more, resort is had to secondary towers for rehandling the distant distribution or to the provision of a plurality of ground supports for the chute line in the form of "cribbing", etc. These necessarily form barriers to operations about the plant, but what is more important of consideration is the disadvantage of immobility, so to speak, of such an arrangement and the very great loss of time and labor when the point of delivery is changed from the zone served by such a chute line.

I am aware further that in large operations, where the topography admits of such use, that cable-way systems are employed, but such systems have so many limitations and disadvantages, particularly where the terrain must be considered, that they are not well adapted to the purpose.

The gravitation system which is the subject matter of my invention, however, has

been devised to overcome the difficulties heretofore experienced in the construction of such large projects as filtration plants, dams, extensive concrete buildings and the like, and in its use and application, I have found it very effective in performing the work with great facility and saving of time and labor, particularly in operations involving a large radius of action.

For the purpose, I provide a preferably centrally arranged elevator tower to which is revolvably connected at one end a catenary support from which is adjustably suspended a chute line of the required length to chute the wet concrete to the desired point of deposit, the other end of the catenary support being connected to anchorages by a specially arranged tackle control, through the instrumentality of which the chute line may be easily and quickly adjusted to effect delivery within a predetermined sector.

With such an arrangement, the chute line is capable of being shifted completely around the central plant to serve any and all sectors of operation without interference from ground supports or the necessity of dismantling or without limitations in reference to any practical radius of action.

Among other objects in view may be mentioned that of providing a rotatable tower head to which the chute line support is connected, whereby tortional strains on the tower are entirely eliminated and the complete rotation of the chute line about the tower is made possible; and further the provision of a remote power control for the distributing chute line, so that at any time, this heavy conveyor may with facility be adjusted as desired by the taking up and simultaneous paying out of tensioning means for the chute support without releasing the normal tension strain on the tower.

A still further advantage resides in the provision for adjustably suspending the chute line from the catenary support whereby the degree of inclination may be regulated to obtain the proper flow of the material as influenced by the state of fluidity of the latter and the distance of the chuting operation.

Other objects and advantages of the invention will be hereinafter set forth and the novel features thereof defined by the appended claims.

In the drawings:—

Figure 1 is a side elevation of the pre-

ferred embodiment of my system, the showing being more or less diagrammatic in character;

Figure 2 is a top plan view thereof;

5 Figure 3 is an enlarged detail elevation of the top of the tower, showing more particularly the connection of the catenary support to the rotatable head of the tower and the guy stay connection at this point;

10 Figure 4 is a top plan view of the construction shown in Figure 3 with the guy cables omitted; and

15 Figure 5 is a vertical sectional view through the turn table device at the top of the tower.

Like numerals refer to like parts in the several figures of the drawing.

Referring to the drawings, in carrying out the system comprehending my invention, 20 I employ an elevator tower 1 located as nearly as possible, centrally of the area to be supplied and at the base of which the mixing plant is preferably arranged. This tower in the main is of conventional construction 25 and is customarily provided with an elevator bucket (not shown) in which the concrete material is hoisted to the desired elevation and automatically dumped into a hopper 2. From the hopper, the concrete 30 flows by way of the chute line 3 to the desired point of deposit, the length of the chute line naturally depending upon the magnitude of the construction "job." To this end, the chute is composed of a plurality 35 of sections, these being added to as the radius of distribution is increased in the course of the work. The chute line is adjustably suspended from a catenary support or cable 4 by means of block and tackles 5, 40 each supported by a trolley wheel 6 which rides upon the cable. These wheels are connected together and are sustained in proper spaced relation by means of a pulley line 7, and as the chute is extended, the inserted 45 chute section necessitates the extension of the pulley line and addition of block and tackle suspensions.

At the end of the chute line, and preferably at points intermediate its length also, 50 there are provided the usual down spouts 8 by means of which the concrete is fed to the desired point of deposit. These appliances are generally known in the construction industry and no claim is therefore made to them per se.

The features of my system which do form the novel characteristics will now be more particularly set forth. In the first place, the connection of the catenary support 4 to the 55 tower and to the ground is of primary importance. As shown particularly in Figures 3 to 5 of the drawing, I mount upon the top of the tower, a turn table device which, in the form herein shown as an exemplification of the idea, is composed of the station-

ary or fixed base section 9 and the superposed rotatable section 10, mounted for rotation upon the shaft 11. For the purpose of fixing the lower section 9 to the tower, U-bolts 12 or the like are employed to connect it to the necessary cribbing on the top of the tower, and as a further detail of construction, U-bolts 13 are utilized to connect the upper section 10 to the eye beams 14 which span the section and rest upon the rim to distribute the stress to the latter. A stop collar 15 prevents displacement of this upper section in the whipping of the cables. It should be understood that this form of turn table device may be modified as required and I do not wish under the conditions to be confined to the specific type herein illustrated. 75

The upper end of the cable 4 is looped about the rotatable section 10 and is fixed thereto by clamp eyes or similar fastening means 16, and it will be obvious that by virtue of the rotatable mounting of the upper end of the cable, its lower end may be revolved about the tower without placing a torsional strain upon the latter. This lower end terminates considerably short of the radius of action and is formed with an eye or loop 17 to which the upper ends of a plurality of tackle lines 18 are connected. The lower end of each tackle device 18 is 85 connected to an anchor 19, any suitable number of which are disposed about the circle of operation of the apparatus.

It will be observed by reference to Figure 2 of the drawings that these tackle control devices assume an angular relation to each other, the tackle line 18' from one extending back to the tower and passing over a sheave 20, then downwardly to and about a winch 21, diagrammatically shown in Figure 1. The tackle lines 18" and 18''' from the other devices correspondingly extend back to the tower over sheaves and downwardly to respective drums. These drums are connected to and driven by a suitable prime mover (not shown) by means of which the tackle lines may be wound upon the drums to exert the necessary tension upon the cable 4 and to maintain such tension. 100

The strain which is necessarily placed upon the tower in supporting the chute line is taken care of by the guy cables 22 connected at their lower ends to anchor posts 23 and at their upper ends to a collar 24 mounted upon the upper end of the shaft 11 of the turn table device. Preferably of course, any number of these cables may be used and others designated 25, are connected to the tower at lower elevations so that, although the tower is usually very high, it is 110 amply supported against the stresses encountered.

It remains to be stated that the anchors 19 which are distributed in substantially a circle about the area in the operation, usually 115

consist of a large block of concrete each having fixed therein a pair of eyes 26, one preferably in advance of the other, but it is obvious to those skilled in the art to which this apparatus appertains, that these anchors may be made a part of any substantial structure so long as they are located at suitable distances from the tower, greater than that of the point of delivery of the chuted concrete, but preferably they are distributed at approximately equal intervals around a circle, their exact location conforming as necessary to topography, obstructions, etc.

In the operation of the system, the mixed concrete is elevated in the tower and dumped into the hopper 2 from which it passes into the chute line and is conveyed its full extent to the end down spout 8 or is shunted from the chute into the other downspouts as the case may require. When it is desired to change the position of the chute line, the hoisting engine operating the drums 21 is started and depending upon which direction the chute is to be shifted, one or the other of the lead lines 18' or 18'' is wound upon the engine drum while the other of the said lines is paid out. This will shorten one of the tackle control devices 18 and simultaneously lengthen the other tackle device, thereby resulting in a displacement of the suspension cable 4 about the tower. The third tackle line 18''' is in the nature of an auxiliary line making it possible to continue chuting operation when changing from one sector to another. That is to say, this third line, if the shift referred to is made toward the dotted line position of Figure 2, is taken up as the line 18' is taken up and when the cable 4 and tackle line 18' reach aligned position, the function of the line 18'' is practically discontinued and taken over by the line 18'. The tackle line 18''' may now be removed from its anchor or shifted to an advance anchor at any time found to be convenient during the distribution in the particular sector in which the lines 18' and 18''' constitute the main support for the cable 4.

The advantage in using the three tackle arrangement resides not only in the saving of time during shifting to succeeding sectors, but also in the maintenance of adequate support for the cable 4, by at least two of such lines at all times. Whipping of the catenary support is practically impossible with such an arrangement. But it will be obvious that the operation may be carried out with two of the tackle devices if desired. This simply results in a loss of time of chuting during the shifting from one sector to another.

In the shifting operation above referred to, it is understood of course that the relation of speed of winding or unwinding of the lead lines is maintained in such a way that the tension of the cable 4 is sustained. Thus the loop 17 at the end of the cable is

retained at the same elevation. It will thus be seen that by this arrangement of the tackle control, the angular position of the catenary support and of the chute line suspended from it may be varied at will by the remote control within the sector between the anchorages to which the control devices 18 are connected.

In the actual use of the apparatus hereinbefore described, it has been found that these shifts from one sector to another can be accomplished without loss of time, whereas in the usual shifting operations of the chute lines of a corresponding operation, the time consumed runs into a day or so. Obviously a very large amount of expense and labor is saved by the method of distribution of this system as compared with the known methods hereinbefore referred to.

What I claim is:

1. In a concrete distributing system, the combination of an elevator tower, a rotatable head thereon, a catenary support connected at one end to said head, means connecting the other end to fixed ground supports and adjustable to shift the catenary support about said tower, and concrete conveying means carried by said catenary support.

2. In a concrete distributing system, the combination of an elevator tower, a rotatable head thereon, a suspension cable fixedly connected at one end to said head, a series of anchorages arranged at spaced intervals about said tower, tensioning means connecting the other end of said tower to certain of said anchorages to sustain said cable at an elevation, and a chute line sustained by said cable and shiftable therewith about the tower to vary the point of delivery of said chute.

3. In a concrete distributing apparatus of the class described, an elevator tower, means in said tower for hoisting material, a turn table device mounted on said tower, a suspension cable connected to the turn table device at one end, tensioning means connecting the other end of the cable to fixed points, said tensioning means being operable to shift the cable rotatably with respect to the tower, while maintaining the tension upon the cable, and a chute line suspended from said cable.

4. In a concrete distributing apparatus of the class described, a catenary support connected at one end to a relatively fixed point, concrete conveyor means suspended from said support, and control means connected to the other end of said support for normally sustaining the same at a relatively fixed elevation and operable to shift the support about the relatively fixed point aforementioned.

5. In a material distributing apparatus of the class described, a catenary support, means carried by said support for conveying

- the material, means connecting one end of said support to spaced relatively fixed points normally sustaining the support at a relatively fixed elevation and adjustable to shift 5 the support and conveying means in either direction about the opposite end of the support and within the zones of said points, and power means for actuating the last mentioned means.
- 10 6. In a concrete distributing apparatus of the class described, a catenary support connected at one end to a relatively fixed point, concrete conveying means suspended from said support, and a tackle control connected 15 to the other end of said support constituting the sole sustaining means therefor and operative independent of the support to shift the support about the relatively fixed points aforementioned, and power actuating 20 means for said tackle control.
7. In a distributing system of the class described, a suspension cable connected at one end to a relatively fixed point, a chute line suspended from said cable to convey 25 material to the desired point of deposit and a tackle control connecting the other end of said cable to spaced relatively fixed points and constituting means for sustaining the support at a fixed elevation, said control being operable from a centralized point to 30 shift the last mentioned cable end about the first mentioned fixed point in opposite directions at will.
8. In a concrete distributing system of the class described, the combination of an elevator tower, a catenary support connected at one end to said tower, a concrete conveyor suspended by said support to carry the concrete to the desired points of deposit, 35 and means angularly related to the catenary support for sustaining the same normally at a relatively fixed elevation and including a central control at the tower operable to shift the support and conveyor about the 40 tower to vary the points of deposit.
9. In a concrete distributing system of the class described, the combination of an elevator tower, a catenary support connected at one end to said tower, a concrete conveyor 45 suspended by said support to carry the concrete to the desired points of deposit, tackle control means for sustaining and shiftably connecting the other end of the catenary support to spaced relatively fixed points, and means centrally arranged for actuating 50 said tackle control means independently of the support to thereby shift the support and conveyor relative to the tower in opposite directions at will.
- 60 10. In a concrete distributing system of the class described, the combination of an elevator tower, a catenary support connected at one end to said tower, a concrete conveyor suspended by said support to carry the 65 concrete to the desired points of deposit, and control means connecting the other end of the catenary support to spaced relatively fixed points, including a pair of angularly related tackle lines extending back to the tower, said lines maintaining a constant 70 tension on the catenary support and being operable to shift the end of the latter toward or from either of the said fixed points at will while maintaining the normal tension on the support. 75
11. In a concrete distributing system of the class described, the combination of an elevator tower, a catenary support connected at one end to said tower, a concrete conveyor suspended by said support to carry the concrete to the desired points of deposit, control means connecting the other end of the catenary support to spaced relatively fixed points, including a plurality or angularly related tackle lines, either of which is operable to 80 shift the support about the tower according to which direction of movement is desired, and centralized control means for simultaneously taking up on one line and paying out the other to thereby shift the support and conveyor relative to the tower. 85
12. In a concrete distributing system, the combination of an elevator tower, a cable line connected at one end to said tower, a chute line suspended from said cable line and extended to the desired point of deposit, and power operating means extending from the other end of the cable line to the tower 90 for shifting the last mentioned end and the chute line about the tower in opposite directions at will to change the point of deposit of the concrete, said power operated means constituting the normal sustaining means for the cable holding it at a fixed elevation. 95
13. In a concrete distributing system, the combination of an elevator tower, a cable having rotatable connection with the tower at one end, a chute line suspended from said cable, a plurality of anchorage means 100 remotely related to the tower and arranged at spaced intervals with respect to each other, and control means comprising tackle lines connecting the other end of the cable to a plurality of said anchors for maintaining tension on said cable, said control means being operable to shift the cable and chute line to change the point of deposit while 105 maintaining tension on the cable. 110
14. In a concrete distributing system of the class described, the combination of a tower, means for hoisting material to an elevation in said tower, a hopper carried by said tower to receive said materials, a chute line to receive the material from said hopper, a cable having rotatable connection at one end to the tower and freely rotatable about the axis of said tower, a control means connecting the other end of the cable to fixed points to maintain the cable under tension, 120 adjustable means suspending the chute line 125
15. In a concrete distributing system of the class described, the combination of an elevator tower, a catenary support connected at one end to said tower, a concrete conveyor suspended by said support to carry the concrete to the desired points of deposit, and control means connecting the other end of the catenary support to spaced relatively fixed points, including a pair of angularly related tackle lines extending back to the tower, said lines maintaining a constant 130 tension on the catenary support and being operable to shift the end of the latter toward or from either of the said fixed points at will while maintaining the normal tension on the support. 135

from said cable and adapted to be adjusted to change the inclination of the chute line at will, and centrally located power means for actuating the control means aforesaid whereby to shift the cable means and chute line about the tower.

15. In a concrete distributing system, the combination of an elevator tower, a cable line connected to said tower at one end, means connected to the other end for shifting the cable to and fro within a sector about the tower, separate means connected to said cable normally sustaining the cable at a fixed elevation for shifting the same from said sector to an adjacent sector and to and fro in the same, and a chute line suspended from said cable.

16. In a concrete distributing system, the

combination of an elevator tower, a cable line connected to said tower at one end, a pair of tackle lines connecting the far end of said cable line to a pair of spaced fixed points said tackle lines being adjustable to shift the cable line about the tower within the zone of the fixed points aforesaid, a separate tackle line connected to the end of the cable line and to a separate fixed point and normally sustaining the cable line with the other tackle lines at a fixed elevation, said separate tackle line being operable to shift the cable line into the zone between the first mentioned pair of fixed points and the third mentioned fixed point, and a chute line suspended from said cable line.

In testimony whereof I affix my signature.
CHARLES H. TOMPKINS.
